His Attorney.

UNITED STATES PATENT OFFICE.

JOHN SCHULDE, OF ST. LOUIS, MISSOURI, ASSIGNOR TO HARRY L. HUSSMANN
REFRIGERATOR & SUPPLY COMPANY, OF ST. LOUIS, MISSOURI, A CORPORATION
OF MISSOURI.

SHOWCASE REFRIGERATOR.

Application filed November 22, 1921. Serial No. 516,935.

To all whom it may concern:

Be it known that I, JOHN SCHULDE, a citizen of the United States, and residing at St. Louis, Missouri, have invented the new and useful Improvement in Showcase Refrigerators, of which the following is a specification.

This invention relates to refrigerators, and more particularly to show-case refrigerators in which the refrigerating compartment is also a display compartment and the refrigerant container is mounted at one end thereof.

One of the objects of this invention is to provide a refrigerant container which shall have a large surface adaptable for contact with the air to be cooled and which shall be arranged to be easily packed with a freezing mixture without danger of clogging.

Another object of this invention is to provide a refrigerating unit arranged so that the air to be cooled may circulate freely about the refrigerant container and in which the brine may be further utilized to cool the air circulating along the bottom of the refrigerating compartment.

Further objects will appear from the detail description taken in connection with the accompanying drawing, in which:—

Figure 1 is a partial longitudinal sectional view of a refrigerator embodying this invention;

Figure 2 is a section on line 2—2, Figure 1; and

Figure 3 is a section on line 3—3, Figure 1.

Referring to the accompanying drawing, the refrigerator comprises a casing 1 of the usual double-walled construction and equipped on the top and sides with double-walled glass panels 2 and 3 respectively. At the end of the refrigerating compartment 4 is located a refrigerant container comprising an upper header 5 having a series of downwardly extending legs 6 opening therefrom and a lower header 7 joining said legs at the bottom.

The header 5 is substantially rectangular in cross-section and is provided at the front thereof facing the refrigerating compartment 4 with a series of perforations 8 through which the air is adapted to enter the refrigerant container so as to come in contact with the freezing mixture. These perforations 8 may be covered with a screen so as to prevent the entrance of foreign mat-

ter. The rear wall of the header 5 is similarly perforated as shown at 9 to allow the air to pass outwardly therefrom.

The legs 6 are open at the bottom and top and are tapering in form being smaller at the bottom so that the freezing mixture may be packed therein. There are a series of these legs spaced from one another so that the air may circulate freely there-around.

The lower header 7 joins the bottoms of the legs 6 which open into it so that the freezing mixture may move downwardly from the leg into the header 7. This header provides a large, cold body directly in the path of the circulating air. The upper walls 10 of the header 7 slope downwardly towards the sides so that water of condensation may be drained off. The lower walls 11 slope downwardly toward the center at which point there is a slot or opening 12 through which the brine may be discharged.

A drip pan 13 is arranged below the refrigerant container to catch the drippings and is provided with an overflow 14 adapted to discharge into a second drip pan 15 extending along the bottom of the refrigerating compartment 4. The brine received from the pan 13 circulates through the pan 15 from which it is discharged through an overflow 16 into a trap 17 in the bottom of the refrigerator from which it may be discharged to the sewer. The pan 15 is constructed as shown in cross-section in Figure 3 having its top wall 18 sloping downwardly toward the outside so as to drain off water of condensation and having its lower wall 19 sloping upwardly toward both sides so as to provide passages 20 for circulation of air under and along the pan 15.

The interior of the refrigerating compartment 4 is provided with shelves 21 for supporting the goods to be cooled.

In operation the goods placed on the shelves 21 tend to warm the air which comes in contact therewith and to deliver to that air certain odors and impurities. This warm air rises to the top of the refrigerating compartment along which it flows to the right, Figure 1, to replace the air which has cooled by contact with the refrigerant container in the end of the compartment. The warmest air flows through the perforations 8 into the refrigerant container whereby contact with the freezing mixture, it is

2 rapidly chilled. By this chilling the moisture carried by the air is condensed and deposited upon the freezing mixture and with it the impurities carried by the air 5 are also deposited. The chilled and purified air passes out through the perforations 9, thence down along the rear of the refrigerant container and outwardly toward the refrigerating compartment 4 passing around 10 and coming into intimate contact with the exterior surfaces of the headers 5 and 7 and the legs 6. By such contact the air is further chilled and caused to move to the bottom of the refrigerating compartment, 15 some of it passing along the surface of the brine in the pan 13. Other portions of the warm air will strike the header 5, become chilled by contact therewith and then pass downward along the legs 6 and 20 over the header 7. The air then flows out along the bottom of the compartment 4, some of it over the top and sides of the pan 15 and some through the passages 20. The air passing through the passages 20 25 is maintained in a chilled condition throughout its travel until it emerges at the end of such passage. In this way cooled air is delivered to the extreme end of the refrigerating compartment 4. The chilled 30 air from the bottom of the compartment 4 rises as it is warmed by contact with the goods on the shelves 21 to the top of said compartment and the circulation is thereafter repeated. In this way a very low 35 temperature can be maintained in the refrigerating compartment.

It will be noted that in the counter refrigerator embodying this invention the elongated show-case provided with transparent 40 panels has mounted at one end thereof a refrigerant container adapted to receive a freezing mixture. This container is constructed and arranged (in the particular embodiment shown, by perforation of the front 45 and back walls at the upper end of the container) to provide a top passage over the freezing mixture in the top of the container, while the arrangement is also such as to provide passages along the back and bottom 50 of the container connecting with the top passage, in order to induce a flow of air through the top passage and down the back passage. The container as well as the drip pan is also 55 adapted and positioned to cause a current of air to circulate in a path from the bottom of the container along the bottom of the show case and in a return path along the top of the show case into the top of the container. This arrangement not only results 60 in keeping the entire show case cool but by directing the current of air along the show case instead of transversely thereto, clouding of the glass panels is avoided. Furthermore any moisture or volatile matter passing 65 over the freezing mixture becomes deposited

therein and on the walls of the container so that the air is maintained dry and odorless.

It is obvious that various changes may be made in details of construction without departing from the spirit of this invention; it is, therefore, to be understood that this invention is not to be limited to the specific details shown and described. 70

Having thus described the invention, what 75 is claimed is:

1. A counter refrigerator comprising, an elongated show-case provided with transparent panels, a freezing mixture container mounted at one end of said show case and 80 consisting of upper and lower headers and legs connecting said headers, said container being constructed and arranged to provide a top passage and passages along its back and bottom connecting with said top passage, in order to induce a flow of air through 85 said top passage and down said back passage, said container being adapted and positioned to cause a current of air to circulate in a path from the bottom of said container 90 along the bottom of the show case and in a return path along the top of the show case into the top of said container.

2. A counter refrigerator comprising, an elongated show-case provided with transparent panels, a freezing mixture container mounted at one end of said show-case and consisting of upper and lower headers and legs connecting said headers, said container being constructed and arranged to provide a top passage and passages along its back and bottom connecting with said top passage, in order to induce a flow of air through 95 said back passage, and a drip pan extending along the bottom of the show-case beyond said container and adapted to receive the brine therefrom, said container and said pan being adapted and positioned to cause a current of air to circulate in a path from the bottom of said container 100 along the bottom of the show-case and in a return path along the top of the show-case into the top of said container. 105

3. A counter refrigerator comprising, an elongated show-case provided with transparent panels, a freezing mixture container mounted at one end of said show-case and consisting of upper and lower headers and legs connecting said headers, said top header being constructed and arranged to provide 110 a top passage over the freezing mixture therein, said container being constructed and arranged to provide passages along its back and bottom connecting with said top passage, in order to induce a flow of air through 115 said top passage and down said back passage, said container being adapted and positioned to cause a current of air to circulate in a path from the bottom of said container 120 along the bottom of the show-case and in a return path along the top of the show-case into the top of said container. 125

130

and in a return path along the top of the show-case into the top of the container.

4. A counter refrigerator comprising, an elongated show-case provided with transparent panels, a freezing mixture container mounted at one end of said show-case and consisting of upper and lower headers and legs connecting said headers, the front and back walls of said top header being perforated to provide a top passage over the freezing mixture therein, said container being constructed and arranged to provide passages along its back and bottom connect-

ing with said top passage, in order to induce a flow of air through said top passage and down said back passage, said container being adapted and positioned to cause a current of air to circulate in a path from the bottom of said container along the bottom of the show-case and in a return path along the top of the show-case into the top of said container.

In testimony whereof I affix my signature this 9th day of May, 1921.

JOHN SCHULDE.
